GAME BOARD

Joseph A. Slais, 425 Shenstone Road, Riverside, Ill.

Filed July 21, 1960, Ser. No. 61,468

Term of patent 14 years

(Cl. D34—5)

The figure is a top plan view of a game board showing my new design. The edge of the game board is of conventional thickness.

I claim:

The ornamental design for a game board, substantially as shown and described.
